Richard T. Clement, Royal Oak, Mich., assignor to General Motors Corporation, Detroit, Mich., a corporation of Delaware

Application April 8, 1958, Serial No. 50,395

Term of patent 7 years

(Cl. D62—4)

Fig. 1

Fig. 2

Fig. 3

Figure 1 is a front elevational view of an air-conditioner cabinet embodying my new design;

Figure 2 is a perspective view showing the front, one side and top thereof; and

Figure 3 is a side elevational view thereof, the opposite side being plain.

The dominant features of the design reside in the portions shown in full lines. The portion broken away in Fig. 3 is for convenience of illustration.

I claim:

The ornamental design for an air conditioner cabinet or similar article, as shown and described.
